UNITED STATES PATENT OFFICE.

ROBERT W. SCOTT, OF BOSTON, MASSACHUSETTS, ASSIGNOR, BY MESNE ASSIGNMENTS,
TO SCOTT & WILLIAMS, INCORPORATED, A CORPORATION OF MASSACHUSETTS.

METHOD OF PREPARING FABRIC SECTIONS.

1,238,717.

Specification of Letters Patent. Patented Aug. 28, 1917.

Application filed August 16, 1915. Serial No. 45,635.

To all whom it may concern:

Be it known that I, ROBERT W. SCOTT, a citizen of the United States, and resident of Boston, in the county of Suffolk and State 5 of Massachusetts, have invented new and useful Improvements in Methods of Preparing Fabric Sections, of which the following is a specification.

My invention relates to the art of knitting on previously knit fabric sections.

One object of my invention is to prepare such a fabric section for further knitting upon it in a manner to decrease the time required and the skill required 15 for preparation. Other objects are to provide a mode of supplying to a series of receiving instruments such as knitting needles or a transfer device, loops of a course of a previously formed fabric section, and then freeing the instruments and the loops of waste fabric in a manner to improve and shorten the operation of knitting fabrics including such sections. As in the prior art, my said method may be practised 20 in connection with a circular or straight series of needles, or a transfer implement such as a ring having quills or points adapted to intermesh with the needles of a knitting machine to which the fabric is to be 25 applied, my invention comprising the step of arranging the fabric to be transferred, in a condition to be knit upon, on the quills or pins of such an implement for a subsequent transfer, or directly on the needles of a knitting machine.

In the accompanying drawings,

Figure 1 is a diagram showing a segment of a transfer implement and a fragment of fabric;

Fig. 2 illustrates a step in the operation;

Fig. 3 is an illustration of the old art string-work, from which the section to be transferred is taken; and

Fig. 4 is a diagram section across the transfer implement illustrating the same time in the operation as Fig. 2.

The usual practice of making a section of fabric, such as a top or rib-top for a stocking, as illustrated in Fig. 3, includes forming 50 a string-work or continuous section of tops each of which may have a welt *w* and a loose-course *C*, the string-work being severed on the lines *s-s* to divide it into individual tops. Each of these tops is man-

ually placed on the needles or the transfer 55 ring or implement, the operator taking the waste fabric *W* between the line of severance *s* and the loose-course *C* in one hand and the part *T* in the other hand, in order to force or "run on" the loose-course, one or 60 more loops at a time, upon the receiving instruments, as the quills *Q* of the transfer ring *R*.

The loose-course *C* may represent one turn of a helix, for instance as illustrated in 65 Fig. 1 occupying the circularly knit helical course numbered 11. The comparatively open loops of this course are brought into line as illustrated, the end loops of the course abutting at one point. The part *T* 70 of the section or top now on one side of the row of receiving instruments illustrated by quills *Q* is to form a part of the stocking or other garment, but the part *W* outside of the quills of the transfer ring, having served 75 its function, must now be removed before the remainder of the operation can be carried out.

In practice, the removal of the waste section *W* takes a large part of the whole time 80 necessary to transfer a section of fabric, owing to the time required to free the edge of the section *W* for raveling. It is impossible when severing such a string-work on the lines *s-s* to cut cleanly through one 85 only of the helical courses, and the edge of the waste section *W* as illustrated in Fig. 1 will be found to contain several fragments, as at *f*, of a course or courses. Each of these fragments must be removed by hand, 90 at the expense of skill and eyesight, before the free running end of a complete course as illustrated at 15', Fig. 1, is unlocked, in order to permit free raveling of the remainder of section *W* to the impaled course *C*. 95 Avoidance of this difficulty has heretofore been attempted by forming the line of severance *s-s* as a course adapted to be broken, or a course adapted to be drawn out; but in the former case irregularities in the structure are produced at the time of breakage, and in the latter case a hard and smooth yarn, which is expensive, must usually be inserted by an expensive special provision in the machine making the string-work. The 100 best practice from the point of view of economy, therefore, has been to cut the string-work as illustrated in Fig. 3, despite

the loss of time occasioned during topping, as above explained.

I have now devised a method of placing as on the quills of the transfer implement 5 and removing the waste part of a cut top such as the rib-top illustrated, which can be carried out with a large gain in respect of the time and skill required. As illustrated in Fig. 1, the waste fabric W may have an 10 edge, as before, containing fragments of a course or courses, and therefore not be in condition to be raveled until the fragments have been removed. To provide a free raveling end at a point in the waste fabric, 15 loose-course C having been impaled, I sever one of the courses of the waste fabric at each sinker-wale between the needle-wales impaled. For instance, if the loose-course C is at the course numbered 11, I may cut the 20 sinker-wales as illustrated at α between each pair of quills, but I prefer to cut the sinker-wales at the next course but one to the course impaled on the quills; that is, to cut the course numbered 13 at the points α' as illustrated, 25 relatively to the impaled course 11. The difficulty above mentioned of cutting systematically the loops of a single course is avoided according to my invention by performing this operation after the impaled course is positioned upon the receiving instruments, the neighboring fabric being positioned by the instruments to enable the intended course to be found by its relation to the fixed instruments, as Q, for certainly 30 cutting the intended course and no other. I prefer to cut all of the sinker-wale loops simultaneously.

The effect of the above step, whether taken in course 12 or course 13, is to leave that part 40 of the waste-fabric W outward beyond the cut course free to be pulled away from the remainder of the top, and to leave the cut ends as at e of each sinker-wale loop of that course which was cut free to be pulled through the needle loop of the course still attached to the main part T of the fabric.

The fabric is now pulled outwardly as illustrated in Fig. 2. The effect of this is to remove the waste fabric with the fragments e , e' , of the loops of course 14 still engaged in the needle-wales in which they were formed, which I attribute to the friction on the cut ends tending to hold them in the place in which they were formed being less than the friction at the engagement of the needle loops of the course 13 with those of course 14.

The waste section W having been removed, the end a of the course 12 is readily 60 found and pulled by the operator, to ravel course 12 once around, thereby freeing the loops of the loose-course C of any part of the waste fabric W, and making them ready for placing on the needles of the machine, 65 or ready for knitting new fabric if the top

has been placed directly on the knitting needles.

I prefer as described to cut the course 13 instead of the course 12, in order to be able to pass the end of yarn which was course 12 70 toward the interior of the fabric, to hold the loop c' from raveling, as will be understood by those skilled in the art. I may also accomplish this same purpose by cutting in the course next to the transfer course C at 75 all the places α , but not cutting at α' , in which case the attached fabric when pulled away will leave an end y to be passed inside the circle of quills.

When I refer to cutting the sinker-wale 80 runs of yarn in a particular course, it will be understood that I refer to severing the yarn in any manner, and that I may employ any convenient implement for this purpose, such as a knife or series of knives or shears, 85 a breaking implement or a burning implement. I may, for instance, employ a series of implements movable together or independently upon or with respect to a transfer ring such as the ring R, to penetrate the 90 sinker-wales and sever a single course at a measured distance from the line determined by the quills Q, but my invention is independent of any implement or machine with the aid of which it may be practised.

In some cases I may practice those steps 95 of my method relating to separating the fabric so as to leave a free raveling edge without performing the remaining steps [for instance to separate a string-work into prepared sections of which one end is free-raveling] by severing the sinker-wale loops as described and then pulling on the fabric to remove all of the yarn fragments from one end of the separated sections. For such employment, it is not essential that the fabric shall be run on to quills or needles, and the instruments supporting it for severing as described may be the instruments upon which it is formed or any other effective 100 support.

What I claim is:

1. The art of separating knit fabric into parts of which one has a free raveling edge comprising severing a course of loops of the 115 fabric at the sinker-wales of the knit structure, and then subjecting the fabric to longitudinal strain.

2. The art of preparing a previously knit fabric section for knitting in continuation 120 thereof comprising running needle loops of a course of said section on a series of receiving instruments, and then severing the yarn extending between the needle wales throughout one course only positioned by 125 its relation to the receiving instruments.

3. The art of preparing a previously knit fabric section for knitting in continuation thereof comprising running a course of knit loops in certain wales of said section on a 130

series of receiving instruments, and then severing the yarn of another course in a plurality of other wales of the fabric.

4. The art of preparing a fabric section for knitting in continuation thereof comprising running a course of said section on a series of receiving instruments, and then severing the yarn in another course thereof, by a series of cuts in a direction longitudinal 10 of the fabric, and then removing together the part of said section beyond the severed course and the fragments of the severed course.

5. The art of preparing a fabric section for knitting in continuation thereof comprising running the needle loops of a course of said section on a series of receiving instruments, and then severing the sinker-wale loops of the yarn of another course thereof, 20 and removing the part of said section beyond the severed course.

6. The art of preparing a fabric section for knitting in continuation thereof comprising running the needle-loops of a course 25 between the ends of said section on a series of receiving instruments, severing the sinker-

wale loops of a course between said instruments and one end of the section, and then removing together a part of the fabric and the fragments of the severed course. 30

7. The art of preparing a fabric section for knitting in continuation thereof comprising running the needle-loops of a course between the ends of said section on a series of receiving instruments, severing the sinker-wale loops of a course between said instruments and one end of the section, then removing together a part of the fabric and the fragments of the severed course, and thereafter raveling a course intervening 35 between said instruments and the severed course. 40

8. The art of separating knit fabrics into parts of which one has a free raveling edge comprising severing a course of loops simultaneously in each sinker-wale, and then pulling the fabric apart at the line of separation so formed. 45

Signed by me at Boston, Massachusetts, this twelfth day of August, 1915.

ROBERT W. SCOTT.
